(57) **CLAIM**

The ornamental design for a stacking pod holder, as shown and described.

DESCRIPTION

FIG. 1 is a perspective view of a stacking pod holder in accordance with my design;

FIG. 2 is a top plan view of the stacking pod holder;

FIG. 3 is a rear elevational view as viewed from the rear of FIG. 1, with the front elevational view being a mirror image thereof;

FIG. 4 is a right side elevational view, with the left side elevational view being identical; and,

FIG. 5 is a bottom plan view thereof.
